(57) **CLAIM**

The ornamental design for a flask as shown and described.

DESCRIPTION

FIG. 1 is a top perspective view of a first embodiment of a flask showing the new design.

FIG. 2 is a front view of the embodiment of FIG. 1, the rear view being a mirror image thereof.

FIG. 3 is a side view of the embodiment of FIG. 1, the opposite side view being a mirror image thereof.

FIG. 4 is a top view of the embodiment of FIG. 1.

FIG. 5 is a bottom view of the embodiment of FIG. 1.

FIG. 6 is a top perspective view of a second embodiment of a flask showing the new design.

FIG. 7 is a front view of the embodiment of FIG. 6, the rear view being a mirror image thereof.

FIG. 8 is a side view of the embodiment of FIG. 6, the opposite side view being a mirror image thereof.

FIG. 9 is a top view of the embodiment of FIG. 6; and,

FIG. 10 is a bottom view of the embodiment of FIG. 6.

The broken lines in the drawings illustrate portions of the flask that form no part of the claimed design.

1 Claim, 8 Drawing Sheets
